(57) **CLAIM**

The ornamental design for an exercise vest as shown and described.

DESCRIPTION

FIG. 1 is a perspective view of the exercise vest of the present invention;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

Portions of the exercise vest shown in broken lines in FIGS. 1-7 form no part of the claimed design. The various styles of surface shading applied to the surfaces of the exercise vest represent a contrast in appearance and do not represent a particular material.
